UNITED STATES PATENT OFFICE.

MEYER L. ROBBINS, OF NEW YORK, N. Y.

WATCH-BRACELET.

1,177,272.

Specification of Letters Patent. Patented Mar. 28, 1916.

Application filed October 29, 1915. Serial No. 58,576.

To all whom it may concern:

Be it known that I, MEYER L. ROBBINS, a citizen of the United States, and a resident of the city, county, and State of New York, and whose post-office address is 333 Central Park west, in said city, have invented certain new and useful Improvements in Watch-Bracelets, of which the following is a specification.

10 This invention relates to a detachable link for the end of a bracelet and means for securing the link to the watch case. Generally the wearer of a watch bracelet desires to use the watch for other purposes, such as 15 a chatelaine, brooch watch, etc., and as a bracelet watch is generally provided with a small link or other means of attachment on its edge, when such a watch is worn as above mentioned, it is readily apparent that a 20 bracelet watch is being used. Thus, convertible watches of this type are not much in use.

The object, therefore, of this invention is to provide a watch case with means to 25 which my improved end link may be secured and detached at will, the means on the watch case not being discernible, so that the wearer can use the watch for other purposes than for a bracelet watch, without it 30 being known that a bracelet watch is being used. These and other improvements are carried out by my invention, a more particular description of which appears below.

Reference is to be had to the accompanying drawings forming part hereof, in which—

Figure 1 is a plan view of a watch with a portion of a bracelet secured thereto; Fig. 2 is a plan view of the detachable link 40 removed from the watch and in open position; Fig. 3 is a view of a portion of the watch case, showing the hinging means and the means for the attachment of the bracelet; Fig. 4 is a sectional view on the line 4—4 45 of Fig. 3, looking in the direction of the arrows; Fig. 5 is a front elevation of the detachable link; Fig. 6 is a sectional view on the line 6—6 of Fig. 2, looking in the direction of the arrows; Fig. 7 is a plan view 50 of a modification of my improved detachable end link; Fig. 8 is a side elevation of the same; Fig. 9 is a perspective view of the same; Fig. 9^a is a plan view, partly in section, of a portion of the above modification; Fig. 10 is a plan view of a further 55 modification; Fig. 11 is a side elevation of

the same; and Fig. 12 is a perspective view of the same.

Throughout the various views of the drawings, similar reference characters designate similar parts.

It is obvious that my improved detachable end link and means for securing the same to the watch case may be used in connection with any form of a bracelet, although in this instance I have shown a so-called expandable bracelet which is made up of a series of outer links 1, and inner links 2 with retracting springs contained between the inner and outer links. The watch 3 has 70 a link 4 to which one end of the bracelet chain is attached, a special form of detachable link 5 being used, if desired.

The back 6 of the watch is hinged to the center 7 by a hinge 8 which is mounted on 75 the pintle 9 which extends through the center of the hinge; recesses 10 being formed in the ends of the hinge.

The detachable end link consists of two resilient side members 11, connected at one 80 end by the cross piece 12, which is engaged by the inner link of the adjoining link. The opposite ends of the side members 11 are off-set as at 13 and on the ends of said off-set portions are formed inwardly extending 85 studs 14 which extend into the recesses 10 in the watch case hinge. A sliding collar 15 is mounted on the link and draws the side members 11 together and holds the studs 14 90 in the recesses 10. Depressions 16 are formed in the side members 11 adjacent the off-set portions 13 to hold the collar 15 in place and prevent the same from inadvertently slipping back and allowing the link to free itself from the watch. A block 17 is 95 secured to the inner side of one of the side members to limit the movement of the side members toward one another when the collar is moved forward into position adjacent the off-set portions 13, and the studs 14 are in 100 position in the recesses 10.

From the foregoing, the operation of the detachable link will be readily understood. To remove the link from the watch, the collar 15 is slid away from the off-set portions 13, which allows the arms 11 to spring away from one another, the studs 14 moving out of the recesses 10 so that the link can be readily removed.

In the embodiment of my invention shown in Figs. 7, 8 and 9, I have shown a link member having two trough-shaped side members

18 connected at the ends by cross pieces 19 and intermediate the ends by a cross piece 20. Slidably mounted in said link is the catch member 21 having resilient tongues 22 and 23. The tongue 23 is slit as at 24, dividing it into two portions 25, the ends of said portions being off-set as at 26 and at the ends of said off-set portions are formed the studs 14 which are adapted to enter the recesses 10 in the watch case hinge. In order to hold the two parts 25 together so that the studs remain in place in the recesses 10, a sliding collar 27 is mounted on the tongue 23. A recess 28 is formed in the tongue 22 which engages the cross-piece 20 to hold the catch member 21 within the link member when the catch member is thus placed. An enlarged serrated portion 29 is formed on the end of the tongue 22 for engagement by the finger nail so that the tongue 22 can be pressed down and the recess 28 forced out of engagement with the cross piece 20 and the catch member drawn out of the link member so that when it is desired to remove the link from the watch, the collar 27 is moved away from the ends 25 allowing them to separate so that the studs come out of engagement with the recesses 10 in the watch case hinge. A recess 30 is formed in the link member for the reception of the collar 27 when the catch member is within the link member. As shown in Fig. 9^a, depressions *a* may be formed in the sides of the ends 25 to hold the collar 27 in position and prevent the same from sliding away and allowing a spreading of the ends.

In the modification shown in Figs. 10, 11 and 12, the link member 31 has the two trough-shaped sides 32 and connecting cross-pieces 33 at its ends. The catch member 34 has two resilient tongues 35 and 36 and a coil spring 37 is placed between the catch member and link member. A sliding collar 37 having openings through which the tongues 35 and 36 pass, is mounted on the catch member 34. The tongue 36 is split, dividing its ends into two portions 38 which ends have off-set portions 39 and the studs 40 on the ends of the off-set portions, which studs enter the recesses 10 formed in the watch case hinge. In order to hold the sliding collar 37 in position adjacent the ends of the tongues 35 and 36, a hump 41 is formed adjacent the free end of the tongue 35, and a serrated portion 42 is formed on the end of the tongue 35, so that the tongue 35 can be pressed downwardly and the hump 41 moved out of engagement with the collar 37 when it is desired to remove the catch from the watch case.

The embodiment of my invention, shown in Figs. 7, 8, 9, 9^a, 10, 11 and 12 is not claimed specifically herein but forms the subject matter of another application.

65 From the foregoing, it is obvious that my

invention may be embodied in various forms and modifications, so I do not limit myself to the exact structure herein shown and described, but believe my invention is broad enough to cover all structures coming within the scope of the annexed claims.

Having described my invention, what I claim is:

1. A fastening means for watch bracelets and the like comprising a laterally expandable link clamp, a projection on a watch case, said link clamp being detachably engageable with said projection and means movable on the link clamp for drawing the sides of the clamp toward one another and holding the same into engagement with the watch case in said contracted position.

2. A fastening means for watch bracelets and the like comprising a watch case having openings therein, a link having a pair of arms adapted to enter the openings in the watch case, and means on said link for drawing said arms toward one another and retaining the same in engagement with said openings.

3. A fastening means for watch bracelets and the like comprising a watch case, having a pair of openings therein, a detachable link having a pair of resilient arms with portions on the ends of said arms for engagement with said openings and a slideable collar on the link for drawing the arms toward one another whereby said arms are retained in engagement with the openings in the watch case.

4. A fastening means for watch bracelets and the like comprising a watch case with a pair of openings formed in the edge of said watch case, a detachable link having a pair of resilient arms, studs formed on the ends of said arms adapted to enter the openings in the watch case, and a collar slideable over said arms for drawing the arms toward one another so that said studs are held in engagement with the openings in the watch case.

5. A fastening means for watch bracelets and the like, comprising a watch case, a hinge on said watch case with a pair of recesses formed in the ends of said hinge, a detachable link having a pair of arms resiliently connected together, studs formed on the ends of said arms adapted to enter the recesses formed in the hinge of the watch case, a sliding collar on said arms adapted to retain the studs in engagement with said recesses and means interposed between the arms for limiting the movement of said arms toward one another.

6. A fastening means for watch bracelets and the like, comprising a watch case, a hinge on said watch case with a recess formed in each end of the hinge, a detachable link having a pair of arms resiliently connected together, off-set portions on the

ends of said arms, studs formed on the ends of said off-set portions and adapted to enter the recesses in the hinge of the watch case and a slidable collar embracing the arms and holding the studs on said arms in engagement with the recesses in the hinge.

7. A fastening means for watch bracelets and the like, comprising a watch case, a hinge on said watch case with a recess formed in each end of the hinge, a detachable link having a pair of arms resiliently connected together, a block interposed between said arms and secured to one of the same, off-set portions on the ends of said arms, studs formed on the ends of said off-set portions and adapted to enter the recesses in the watch case hinge and a slidable collar embracing the arms and holding the studs

on said arms in engagement with the recesses in the hinge.

8. A fastening means for watch bracelets and the like, comprising a watch case, a hinge for said watch case mounted on a pintle, said pintle extending a portion of the way through said hinge, leaving recesses in the ends thereof, a detachable link having a pair of arms resiliently connected together, studs formed on the ends of said arms adapted to enter the recesses in the watch case hinge and a slidable collar embracing the arms and holding the same in engagement with said recesses.

Signed at the city, county and State of New York, this 28th day of October, 1915.

MEYER L. ROBBINS.
